(57) **ABSTRACT**

Disclosed herein is a coil component that includes a resin body having a first resin-based insulating material and a second resin-based insulating material lower in relative permittivity than the first resin-based insulating material, a coil pattern embedded in the resin body and helically wound in a plurality of turns, and first and second terminal electrodes formed on a surface of the resin body and connected respectively to one and other ends of the coil pattern. The coil pattern has a part covered with the first resin-based insulating material and another part covered with the second resin-based insulating material.

COIL COMPONENT

BACKGROUND OF THE INVENTION

Field of the Invention

The present invention relates to a coil component and, more particularly, to a coil component having a structure in which a helical coil pattern is embedded in a resin body.

Description of Related Art

As a coil component having a structure in which a helical coil pattern is embedded in a resin body, a coil component described in JP 2006-324489A is known.

However, in the coil component described in JP 2006-324489A, it is difficult to sufficiently increase a self-resonance frequency (SRF).

SUMMARY

It is therefore an object of the present invention to increase a self-resonance frequency in a coil component having a structure in which a helical coil pattern is embedded in a resin body.

A coil component according to the present invention includes: a resin body having a first resin-based insulating material and a second resin-based insulating material lower in relative permittivity than the first resin-based insulating material; a coil pattern embedded in the resin body and helically wound in a plurality of turns; and first and second terminal electrodes formed on the surface of the resin body and connected respectively to one and the other ends of the coil pattern. The coil pattern has a part covered with the first resin-based insulating material and another part covered with the second resin-based insulating material.

According to the present invention, sufficient mechanical strength can be ensured by the first resin-based insulating material, and floating capacitance can be reduced by the second resin-based insulating material low in relative permittivity. This can increase a self-resonance frequency.

In the present invention, the second resin-based insulating material may be provided between the first and second terminal electrodes and the coil pattern. This can reduce the floating capacitance between the first and second terminal electrodes and the coil pattern.

In the present invention, the second resin-based insulating material may be provided between adjacent turns of the coil pattern. This can reduce the floating capacitance generated between adjacent turns of the coil pattern.

In the present invention, the resin body may include a first resin layer, a second resin layer, and a third resin layer provided between the first and second resin layers, the coil pattern may include a plurality of first horizontal sections provided on the first resin layer and embedded in the third resin layer, a plurality of second horizontal sections provided on the third resin layer and embedded in the second resin layer, a plurality of first vertical sections penetrating the third resin layer and connecting each of one ends of the plurality of first horizontal sections to each of one ends of the plurality of second horizontal sections, and a plurality of second vertical sections penetrating the third resin layer and connecting each of the other ends of the plurality of first horizontal sections to each of other ends of the plurality of second horizontal sections. With this configuration, the coil axis of the coil pattern can be made perpendicular to the stacking direction of the resin layers.

2

In this case, the first and second terminal electrodes are provided on the second resin layer, wherein the second resin layer may be made of the second resin-based insulating material, and wherein a part of the third resin layer that embeds the first horizontal section therein may be made of the second resin-based insulating material, while the remaining part thereof may be made of the first resin-based insulating material. In the former case, the floating capacitance generated between the first and second terminal electrodes and the second horizontal sections of the coil pattern and the floating capacitance generated between adjacent second horizontal sections can be reduced. In the latter case, the floating capacitance between adjacent first horizontal sections can be reduced.

In the present invention, the first and second terminal electrodes may be arranged in the axial direction of the coil pattern. This reduces a potential difference between the first and second terminal electrodes and the coil pattern, thereby further reducing floating capacitance.

In this case, the first and second terminal electrodes may be formed on the surface of the resin body parallel to the axial direction without being formed on the surface thereof perpendicular to the axial direction. This makes magnetic flux less likely to interface with the first and second terminal electrodes, thereby suppressing the occurrence of an eddy current.

In the present invention, the first resin-based insulating material may be added with filler, while the second resin-based insulating material is added with no filler. This can further enhance the strength of the first resin-based insulating material and further reduce the relative permittivity of the second resin-based insulating material.

According to the present invention, it is possible to increase the self-resonance frequency in a coil component having a structure in which a helical coil pattern is embedded in a resin body.

BRIEF DESCRIPTION OF THE DRAWINGS

The above features and advantages of the present disclosure will be more apparent from the following description of certain preferred embodiments taken in conjunction with the accompanying drawings, in which:

FIGS. 1A and 1B are schematic transparent perspective views for explaining the configuration of a coil component 1 according to a first embodiment of the present invention, where FIG. 1A is a view as viewed from the top surface side, and FIG. 1B is a view as viewed from the mounting surface side;

FIG. 2 is a schematic cross-sectional view taken along the line A-A in FIG. 1B.

FIG. 3 is a schematic perspective view for explaining the structure of the coil pattern C embedded in the resin body 10;

FIG. 4 is a schematic transparent plan view of the coil pattern C as viewed in the z-direction;

FIG. 5 is a process view for explaining the manufacturing method for the coil component 1;

FIGS. 6A to 11C are process views for explaining the manufacturing method for the coil component 1, where FIGS. 6A, 7A, 8A, 9A, 10A, and 11A are schematic perspective views, FIGS. 6B, 7B, 8B, 9B, 10B, and 11B are schematic plan views, and FIGS. 6C, 7C, 8C, 9C, 10C, and 11C are schematic cross-sectional views taken along the line B-B in FIGS. 6B, 7B, 8B, 9B, 10B, and 11B, respectively;

FIG. 12 is a schematic cross-sectional view for explaining the configuration of a coil component 2 according to a second embodiment of the present embodiment;

FIG. 13 is a schematic cross-sectional view for explaining the configuration of a coil component 3 according to a third embodiment of the present invention;

FIGS. 14A and 14B are schematic transparent perspective views for explaining the configuration of a coil component 4 according to a fourth embodiment of the present invention, where FIG. 14A is a view as viewed from the top surface side, and FIG. 14B is a view as viewed from the mounting surface side; and

FIGS. 15A and 15B are schematic transparent perspective views for explaining the configuration of a coil component 5 according to a fifth embodiment of the present invention, where FIG. 15A is a view as viewed from the top surface side, and FIG. 15B is a view as viewed from the mounting surface side.

DETAILED DESCRIPTION OF THE EMBODIMENTS

Preferred embodiments of the present disclosure will be explained below in detail with reference to the accompanying drawings.

First Embodiment

FIGS. 1A and 1B are schematic transparent perspective views for explaining the configuration of a coil component 1 according to a first embodiment of the present invention. FIG. 1A is a view as viewed from the top surface side, and FIG. 1B is a view as viewed from the mounting surface side. FIG. 2 is a schematic cross-sectional view taken along the line A-A in FIG. 1B.

The coil component 1 according to the first embodiment is a surface-mountable chip-type electronic component and includes, as illustrated in FIGS. 1A, 1B and 2, a resin body 10, a coil pattern C embedded in the resin body 10, and terminal electrodes E1 and E2 provided on the surface of the resin body 10.

The resin body 10 has a structure in which four resin layers 11 to 14 are stacked in this order in the z-direction. The resin layers 11 and 13 are made of a resin-based insulating material obtained by adding filler such as silica to an epoxy- or acrylic-based resin material. The resin-based insulating material constituting the resin layer 11 and that constituting the resin layer 13 may be the same or different. The resin layers 12 and 14 are made of a resin material including no filler, such as bismaleimide or liquid crystal polymer. The resin-based insulating material constituting the resin layer 12 and that constituting the resin layer 14 may be the same or different.

Thus, the resin-based insulating material constituting the resin layers 11 and 13 is higher in strength and processability than that constituting the resin layers 12 and 14. On the other hand, the resin-based insulating material constituting the resin layers 12 and 14 is made of a resin material having a low relative permittivity and is added with no filler such as silica and is thus lower in relative permittivity than the resin-based insulating material constituting the resin layers 11 and 13. For example, the resin-based insulating material constituting the resin layers 11 and 13 has a relative permittivity E of about 3.3 at 1 GHz, and the resin-based insulating material constituting the resin layers 12 and 14 has a relative permittivity E of about 2.4 at 1 GHz.

FIG. 3 is a schematic perspective view for explaining the structure of the coil pattern C embedded in the resin body 10. FIG. 4 is a schematic transparent plan view of the coil pattern C as viewed in the z-direction.

As illustrated in FIGS. 2 to 4, the coil pattern C includes horizontal sections (first horizontal sections 31 to 34 and second horizontal sections 41 to 45) extending in the xy plane and vertical sections (first vertical sections 51 to 54 and second vertical sections 61 to 64) extending in the z-direction. As illustrated in FIG. 2, the first horizontal sections 31 to 34 are provided on the surface of the resin layer 11 and embedded in the resin layer 12. The second horizontal sections 41 to 45 are provided on the surface of the resin layer 13 and embedded in the resin layer 14. The first vertical sections 51 to 54 and second vertical sections 61 to 64 are each provided so as to penetrate the resin layers 12 and 13. The first vertical sections 51 to 54 connect the first horizontal sections 31 to 34 and second horizontal sections 41 to 44, respectively, at their one ends. The second vertical sections 61 to 64 connect the first horizontal sections 31 to 34 and second horizontal sections 42 to 45, respectively, at their other ends.

With the above configuration, the coil pattern C helically wound in a plurality of turns can be obtained. The coil pattern C has a coil axis extending in the x-direction. The other end of the second horizontal section constitutes one end of the coil pattern C and is connected to the terminal electrode E1 through a via conductor 71 penetrating the resin layer 14. One end of the second horizontal section 45 constitutes the other end of the coil pattern C and is connected to the terminal electrode E2 through a via conductor 72 penetrating the resin layer 14. The terminal electrodes E1 and E2 are each a bottom-surface terminal formed only on the xy surface of the resin body 10. That is, the terminal electrodes E1 and E2 do not cover the yz surface of the resin body 10, so that when the coil component 1 is mounted on a circuit board using a solder, the yz surface of the resin body 10 is not covered with solder fillets. This improves a mounting density. Further, magnetic flux generated from the coil pattern C is made less likely to interfere with the terminal electrodes E1, E2 and solder, making it possible to suppress the occurrence of an eddy current.

As illustrated in FIG. 4, the terminal electrode E1 overlaps at least the second horizontal section 41, and the terminal electrode E2 overlaps at least the second horizontal section 45. Thus, floating capacitance is generated between the terminal electrode E1 and the second horizontal section 41 and between the terminal electrode E2 and the second horizontal section 45. However, in the present embodiment, the resin layer 14 positioned both therebetween is made of a resin-based insulating material having a low relative permittivity, making it possible to reduce the floating capacitance generated between the terminal electrode E1, E2 and the second horizontal sections 41 and 45. In addition, the second horizontal sections 41 to 45 are embedded in the resin layer 14, so that the floating capacitance between the second horizontal sections 41 to 45 adjacent to one another in the x-direction, that is, the floating capacitance generated between adjacent turns of the coil pattern C can be reduced. This makes it possible to prevent a decrease in a self-resonance frequency due to floating capacitance.

Further, in the present embodiment, the terminal electrode E1 also overlaps a part of the second horizontal section 42, and the terminal electrode E2 also overlaps a part of the second horizontal section 44. Thus, floating capacitance is also generated between the terminal electrode E1 and the

second horizontal section 42 and between the terminal electrode E2 and the second horizontal section 44. The second horizontal section 42 has a longer wiring distance from the terminal electrode E1 than the second horizontal section 41, so that the floating capacitance of the terminal electrode E1 and second horizontal section 42 per unit area is larger than the floating capacitance of the terminal electrode E1 and second horizontal section 41 per unit area due to influence of a voltage drop. Similarly, the second horizontal section 44 has a longer wiring distance from the terminal electrode E2 than the second horizontal section 45, so that the floating capacitance of the terminal electrode E2 and second horizontal section 44 per unit area is larger than the floating capacitance of the terminal electrode E2 and second horizontal section 45 per unit area due to influence of a voltage drop. When the terminal electrodes E1 and E2 each thus overlap some of the second horizontal sections 41 to 45, the effect of the use of a resin-based insulating material having a low relative permittivity as the material of the resin layer 14 becomes larger.

Further, in the present embodiment, the first horizontal sections 31 to 34 are embedded in the resin layer 12, and the resin layer 12 is made of a resin-based insulating material having a low relative permittivity, so that the floating capacitance between the first horizontal sections 31 to 34 adjacent to one another in the x-direction, that is, the floating capacitance generated between adjacent turns of the coil pattern C can be reduced.

The first vertical sections 51 to 54 and second vertical sections 61 to 64 mostly penetrate the resin layer 13 having high strength, making it possible to ensure sufficient mechanical strength of the entire resin body 10. To ensure mechanical strength of the resin body 10, a thickness T13 of the resin layer 13 is preferably three or more times the thicknesses T12 and T14 of the resin layers 12 and 14. For example, by setting the T12, T13, and T14 to about 20 μm , about 115 μm , and about 30 μm , respectively, it is possible to reduce floating capacitance while ensuring mechanical strength of the resin body 10.

As described above, in the coil component 1 according to the present embodiment, the coil pattern C is embedded in the resin body 10 and is covered with the resin layers 11 and 13 made of a resin-based insulating material having high strength and the resin layers 12 and 14 made of a resin-based insulating material having a low relative permittivity, so that it is possible to prevent a reduction in a self-resonance frequency due to floating capacitance while ensuring mechanical strength of the resin body 10.

Further, in the present embodiment, the terminal electrodes E1 and E2 are arranged in the axial direction (x-direction) of the coil pattern C, so that the terminal electrode E1 does not overlap the second horizontal sections (e.g., second horizontal sections 44 and 45) having a comparatively longer wiring distance therefrom and, similarly, the terminal electrode E2 does not overlap the second horizontal sections (e.g., second horizontal sections 41 and 42) having a comparatively longer wiring distance therefrom. This reduces the difference between a potential between the terminal electrodes E1 and the second horizontal sections 41 and 42 overlapping the terminal electrode E1 and a potential between the terminal electrodes E2 and the second horizontal sections 44 and 45 overlapping the terminal electrode E2, so that it is possible to further reduce floating capacitance as compared with a case where the terminal electrodes E1 and E2 are arranged in the y-direction.

The following describes a manufacturing method for the coil component 1 according to the present embodiment.

FIG. 5 and FIGS. 6A to 11C are process views for explaining the manufacturing method for the coil component 1 according to the present embodiment. FIGS. 6A, 7A, 8A, 9A, 10A, and 11A are schematic perspective views, FIGS. 6B, 7B, 8B, 9B, 10B, and 11B are schematic plan views, and FIGS. 6C, 7C, 8C, 9C, 10C, and 11C are schematic cross-sectional views taken along the line B-B in FIGS. 6B, 7B, 8B, 9B, 10B, and 11B, respectively.

As illustrated in FIG. 5, a support substrate 80 made of a 10 ceramic material such as alumina or non-magnetic ferrite is prepared, and the resin layer 11 is formed on the surface of the support substrate 80. Then, as illustrated in FIGS. 6A to 15 6C, the first horizontal sections 31 to 34 are formed on the surface of the resin layer 11. The first horizontal sections 31 to 34 are formed as follows: forming a thin feeding film on the entire surface of the resin layer 11; attaching a photo-sensitive film, followed by exposure and development, to form openings in the photo-sensitive film; and growing the first horizontal sections 31 to 34 in the respective openings 20 by electrolyte plating. Since the resin layer 11 is made of a resin-based insulating material having high strength, it is possible to ensure high processing accuracy for the first horizontal sections 31 to 34 formed thereon.

Then, as illustrated in FIGS. 7A to 7C, the resin layer 12 25 is formed on the surface of the resin layer 11 so as to embed the first horizontal sections 31 to 34 therein. Thus, the first horizontal sections 31 to 34 adjacent to one another in the x-direction are insulated from one another by a resin-based insulating material having a low relative permittivity. Then, 30 openings 31a to 34a and 31b to 34b are formed in the resin layer 12 to expose both end portions of the first horizontal sections 31 to 34 therethrough.

Then, as illustrated in FIGS. 8A to 8C, there are formed 35 the first vertical sections 51 to 54 connected respectively to one ends of the first horizontal sections 31 to 34 through the openings 31a to 34a and the second vertical sections 61 to 64 connected respectively to the other ends of the first horizontal sections 31 to 34 through the openings 31b to 34b. The first vertical sections 51 to 54 and second vertical 40 sections 61 to 64 are formed as follows: forming a thin feeding film on the entire surface of the resin layer 12; attaching a photo-sensitive film, followed by exposure and development, to form openings in the photo-sensitive film; and growing the first vertical sections 51 to 54 and second vertical 45 sections 61 to 64 in the respective openings by electrolyte plating.

Then, as illustrated in FIGS. 9A to 9C, the resin layer 13 50 is formed so as to embed the first vertical sections 51 to 54 and second vertical sections 61 to 64 therein. The resin layer 13 is formed as follows: peeling the photo-sensitive film used 55 for forming the first vertical sections 51 to 54 and second vertical sections 61 to 64; laminating an uncured sheet constituting the resin layer 13 and curing the sheet; and polishing the sheet surface to expose the top portions of the 60 respective first and second vertical sections 51 to 54 and 61 to 64. The processes illustrated in FIGS. 8A to 8C and 9A to 9C may be alternately repeated a plurality of times until a target height of the first vertical sections 51 to 54 and second vertical sections 61 to 64 is achieved. Since the resin layer 13 is made of a resin-based insulating material having high strength, it is possible to ensure high processing accuracy for the first vertical sections 51 to 54 and second vertical sections 61 to 64.

Then, as illustrated in FIGS. 10A to 10C, the second 65 horizontal sections 41 to 45 are formed on the surface of the resin layer 13. The second horizontal sections 41 to 45 may be formed according to the same procedure as for the first

horizontal sections **31** to **34**. Since the resin layer **13** is made of a resin-based insulating material having high strength, it is possible to ensure high processing accuracy for the second horizontal sections **41** to **45** formed thereon.

Then, as illustrated in FIGS. 11A to 11C, the resin layer **14** is formed on the surface of the resin layer **13** so as to embed the second horizontal sections **41** to **45** therein. Thus, the second horizontal sections **41** to **45** adjacent to one another in the x-direction are insulated from one another by a resin-based insulating material having a low relative permittivity. Then, openings **71a** and **72a** are formed in the resin layer **14** to expose the other end of the second horizontal section **41** and one end of the second horizontal section **45** therethrough. Finally, the terminal electrodes **E1** and **E2** are formed at positions overlapping the respective openings **71a** and **72a**, whereby the coil component **1** according to the present embodiment is completed.

As described above, in the manufacturing method for the coil component **1** according to the present embodiment, the first horizontal sections **31** to **34** and second horizontal sections **41** to **45** are formed respectively on the resin layers **11** and **13** high in strength and processability, and the first vertical sections **51** to **54** and second vertical sections **61** to **64** mostly penetrate the resin layer **13** high in strength and processability. Thus, higher processing accuracy can be ensured as compared with a case where the entire resin body **10** is constituted by a resin-based insulating material having a low relative permittivity.

Second Embodiment

FIG. 12 is a schematic cross-sectional view for explaining the configuration of a coil component **2** according to a second embodiment of the present embodiment.

As illustrated in FIG. 12, the coil component **2** according to the second embodiment differs from the coil component **1** according to the first embodiment in that the resin layer **12** is made of the same resin-based insulating material as those of the resin layers **11** and **13**. Other configurations are the same as those of the coil component **1** according to the first embodiment, so the same reference numerals are given to the same elements, and overlapping description will be omitted. As exemplified by the coil component **2** according to the second embodiment, the first horizontal sections **31** to **34** need not necessarily be covered with a resin-based insulating material having a low relative permittivity in the present invention.

Third Embodiment

FIG. 13 is a schematic cross-sectional view for explaining the configuration of a coil component **3** according to a third embodiment of the present invention.

As illustrated in FIG. 13, the coil component **3** according to the third embodiment differs from the coil component **1** according to the first embodiment in that the resin layer **14** is made of the same resin-based insulating material as those of the resin layers **11** and **13**. Other configurations are the same as those of the coil component **1** according to the first embodiment, so the same reference numerals are given to the same elements, and overlapping description will be omitted. As exemplified by the coil component **3** according to the third embodiment, the second horizontal sections **41** to **45** need not necessarily be covered with a resin-based insulating material having a low relative permittivity in the present invention.

Fourth Embodiment

FIGS. 14A and 14B are schematic transparent perspective views for explaining the configuration of a coil component **4** according to a fourth embodiment of the present invention. FIG. 14A is a view as viewed from the top surface side, and FIG. 14B is a view as viewed from the mounting surface side.

As illustrated in FIGS. 14A and 14B, the coil component **4** according to the fourth embodiment differs from the coil component **1** according to the first embodiment in that the coil pattern **C** embedded in the resin body **10** has a coil axis extending in the z-direction. One end of the coil pattern **C** is connected to the terminal electrode **E1** through a lead-out wiring **Ca**, and the other end thereof is connected to the terminal electrode **E2**.

As the material of the resin layer **14** positioned between the terminal electrodes **E1**, **E2** and a first pattern of the coil pattern **C** starting from the terminal electrode **E2**, a resin-based insulating material having a low relative permittivity is used. The coil pattern **C** is mostly embedded in the resin layer **13** having high strength. Further, the resin layer **12** positioned between predetermined adjacent turns of the coil pattern **C** is also made of a resin-based insulating material having a relative permittivity lower than that of the resin layer **13**. This makes it possible to reduce the floating capacitance generated between the terminal electrodes **E1**, **E2** and the first turn of the coil pattern **C** and the floating capacitance generated between predetermined adjacent turns of the coil pattern **C**.

As exemplified by the coil component **4** according to the fourth embodiment, the coil pattern **C** may have a coil axis extending in the stacking direction (z-direction) in the present invention.

Fifth Embodiment

FIGS. 15A and 15B are schematic transparent perspective views for explaining the configuration of a coil component **5** according to a fifth embodiment of the present invention. FIG. 15A is a view as viewed from the top surface side, and FIG. 15B is a view as viewed from the mounting surface side.

As illustrated in FIGS. 15A and 15B, the coil component **5** according to the fifth embodiment differs from the coil component **4** according to the fourth embodiment in that the resin layer **12** is omitted. Other configurations are the same as those of the coil component **4** according to the fourth embodiment, so the same reference numerals are given to the same elements, and overlapping description will be omitted. As exemplified by the coil component **5** according to the fifth embodiment, the entire coil pattern **C** may be embedded in the resin layer **13**, and the resin layer **14** having a low relative permittivity may be disposed only between the terminal electrodes **E1**, **E2** and the first turn of the coil pattern **C**.

It is apparent that the present disclosure is not limited to the above embodiments, but may be modified and changed without departing from the scope and spirit of the disclosure.

For example, in the above embodiments, the resin-based insulating material constituting the resin layers **11** and **13** is added with filler, while the resin-based insulating material constituting the resin layers **12** and **14** is added with no filler; however, this is not essential in the present invention. Further, the same resin material may be used for the resin layers **11**, **13** and resin layers **12**, **14** with filter added to the

resin layers 11, 13 so as to enhance strength and with no filler added to the resin layers 12, 14 so as not to increase the relative permittivity.

What is claimed is:

1. A coil component comprising:
a resin body having a first resin-based insulating material and a second resin-based insulating material lower in relative permittivity than the first resin-based insulating material;
a coil pattern embedded in the resin body and helically wound in a plurality of turns; and
first and second terminal electrodes formed on a surface of the resin body and connected respectively to one and other ends of the coil pattern,
wherein the coil pattern has a part covered with the first resin-based insulating material and another part covered with the second resin-based insulating material,
wherein the second resin-based insulating material is provided between the first and second terminal electrodes and the coil pattern, and the first resin-based insulating material is not provided therebetween,
wherein the first and second terminal electrodes are arranged in an axial direction of the coil pattern,
wherein the first and second terminal electrodes are formed on the surface of the resin body parallel to the axial direction without being formed on another surface thereof perpendicular to the axial direction,
wherein the resin body includes a first resin layer, a second resin layer formed on a surface of the first resin layer, and a third resin layer formed on a surface of the second resin layer,
wherein the first and third resin layers are made of the first resin-based insulating material, and the second resin layer is made of the second resin-based insulating material,
wherein the coil pattern includes:
a plurality of first horizontal sections provided on the surface of the first resin layer and embedded in the second resin layer;
a plurality of second horizontal sections provided on a surface of the third resin layer;
a plurality of first vertical sections penetrating the second and third resin layers and connecting each of one ends of the plurality of first horizontal sections to each of one ends of the plurality of second horizontal sections; and
a plurality of second vertical sections penetrating the second and third resin layers and connecting each of other ends of the plurality of first horizontal sections to each of other ends of the plurality of second horizontal sections,
wherein the resin body further includes a fourth resin layer formed on the surface of the third resin layer,
wherein the first and second terminal electrodes are provided on the fourth resin layer, and
wherein the fourth resin layer is made of the second resin-based insulating material.

2. The coil component as claimed in claim 1, wherein the second resin-based insulating material is provided between adjacent turns of the coil pattern.
3. The coil component as claimed in claim 1,
wherein a part of the third resin layer that embeds the first horizontal section therein is made of the second resin-based insulating material, and
wherein a remaining part of the third resin layer is made of the first resin-based insulating material.
4. The coil component as claimed in claim 1,
wherein the first resin-based insulating material is added with filler, and
wherein the second resin-based insulating material is added with no filler.
5. A coil component comprising:
a first resin layer;
a plurality of first coil sections formed on the first resin layer;
a second resin layer formed on the first resin layer so as to embed therein the plurality of first coil sections;
a third resin layer formed on the second resin layer;
a plurality of second coil sections formed on the third resin layer;
a fourth resin layer formed on the third resin layer so as to embed therein the plurality of second coil sections;
a plurality of third coil sections each connected between one end of an associated one of the plurality of first coil sections and one end of an associated one of the plurality of second coil sections;
a plurality of fourth coil sections each connected between other end of an associated one of the plurality of first coil sections and other end of an associated one of the plurality of second coil sections; and
a terminal electrode formed on the fourth resin layer and connected to a predetermined one of the plurality of second coil sections,
wherein the fourth resin layer is lower in relative permittivity than the third resin layer, and
wherein no resin layer having relative permittivity higher than that of the fourth resin layer is present between the plurality of the second coil sections and the terminal electrode.
6. The coil component as claimed in claim 5, wherein the fourth resin layer is lower in relative permittivity than the first resin layer.
7. The coil component as claimed in claim 5, wherein the third resin layer is thicker than the fourth resin layer.
8. The coil component as claimed in claim 7, wherein a thickness of the third resin layer is more than three times a thickness of the fourth resin layer.
9. The coil component as claimed in claim 5, wherein the second resin layer is lower in relative permittivity than the third resin layer.
10. The coil component as claimed in claim 5, wherein the second resin layer is lower in relative permittivity than the first resin layer.
